Filed Oct. 14, 1968, Ser. No. 13,981

Term of patent 14 years

Int. Cl. D26—03

U.S. Cl. D48—31

FIG. 1 is a perspective view of a lighting standard, incorporating our invention;

FIG. 2 is a enlarged view in side elevation thereof;

FIG. 3 is a view in horizontal section along the line 3—3 of FIG. 2; and

FIG. 4 is a enlarged view in end elevation thereof.

The pavement and the second lighting standard in FIG. 1 are shown in broken lines for illustrative purposes only.

The lighting standard is broken away in FIGS. 2 and 4 for convenience of illustration.

We claim:

The ornamental design for a lighting standard, substantially as shown and described.
